PLASTIC SHEET MATERIAL

William P. Rowland, Millbrook Lane, Southington, Conn.

Filed Mar. 3, 1965, Ser. No. 84,058

Term of patent 14 years

(Cl. D87—3)

FIG. 1

FIG. 2

FIG. 3

FIGURE 1 is a top plan view of the full width of a plastic sheet material embodying my new design; FIGURE 2 is a bottom view thereof; and FIGURE 3 is a sectional view along the line 3—3 of FIGURE 1.

The synthetic plastic sheet material includes an undulating band of color in the center portion of the sheet material which is distinct from the color of the remainder of the sheet material and which is illustrated in FIGURE 1 by the undulating band shown in phantom line and by the stippling in FIGURE 2. The intensity and depth of color in the band are substantially uniform along the length of the sheet material but diminish toward the side edges of the sheet material as shown by the cross section in FIGURE 3 and the intensity of stippling in FIGURE 2. The color is therefore more intense at the center of

the band and fades gradually toward the side margins of the band. The central design shown in FIGURE 1 is a pattern formed within the colored band and repeats along the length of the sheet material.

I claim:

The ornamental design for plastic sheet material, as shown and described.
